United States Patent Office

Des. 195,355
Patented June 4, 1963

195,355

LIQUID LEVEL GAUGE

Paul B. Johnson, Garland, Tex., assignor to J. Y. Taylor
Manufacturing Company, a corporation of Texas

Filed May 25, 1960, Ser. No. 60,723

Term of patent 14 years

(Cl. D52—6)

FIG. 1 is a perspective view of a liquid level gauge embodying my new design;

FIG. 2 is a perspective view from the opposite side thereof with portions shown in broken lines in FIG. 1 omitted for convenience of illustration.

FIG. 3 is a top plan view thereof with portions shown in broken lines in FIG. 1 omitted for convenience of illustration.

The dominant features of the design are shown in full lines in the drawing.

I claim:

The ornamental design for a liquid level gauge, substantially as shown and described.
